SEAL FOR FANS

Robert D. Moore, Kansas City, Mo., assignor to
The Moore Company, Kansas City, Mo., a corporation of Missouri

Application December 29, 1945, Serial No. 638,189

4 Claims. (Cl. 230—120)

1

This invention relates to fans and particularly to a seal for closing space between the tips of the blades of a fan and the flow control ring in which the blades turn. In fans of relatively large diameter it has been impossible to establish and maintain close tolerance between the tips of the blades and the surrounding ring because of difficulty in maintaining roundness of the ring and concentricity of the fan. Consequently, such fans are constructed with sufficient clearance to allow for adequate clearance of the blades so as to avoid striking thereof against any part of the ring. Therefore, considerable efficiency is lost by eddy currents at the tips of the blades, that is, the air propelled by the blades spills backwardly through such space.

It is the purpose of the present invention to provide a seal for maintaining close tolerance at the tips of the blades regardless of eccentric location of the fan or any out-of-roundness of the control ring.

A further object of the invention is to provide a seal that can be maintained throughout the life of the fan even though the shape of the ring or eccentric relationship between the fan and control ring may change.

In accomplishing these and other objects of the invention, I have provided improved structure, the preferred form of which is illustrated in the accompanying drawing wherein:

Fig. 1 is a vertical section through a fan unit equipped with a seal constructed in accordance with the present invention.

Fig. 2 is a fragmentary perspective section of the fan unit.

Fig. 3 is a similar perspective section of a modified form of seal.

Fig. 4 is a similar section of a further modified form of seal.

Referring more in detail to the drawing:

I designates a fan which may be of large diameter such as a fan used in wind tunnels, induced or forced draft cooling towers, air conditioning systems and the like. The fan includes a hub 2 and radially arranged blades 3 fixed thereto and adapted to rotate within a flow control ring or frame member 4. The fan is mounted on a shaft 5 to which the hub 2 is attached, the hub 2 being supported as near as possible in concentric relation with the ring 4. In the present illustration, the ring 4 includes a web portion 6 encircling the fan and may be of cylindrical formation; however, the ring may be coned or otherwise formed without departing from the spirit of the invention. The sides of the ring may be rein-

forced by circumferential flanges 7 and 8 with which the ring is attached to the structure in which it is used.

As above stated, it is difficult to form such rings in a perfect circle, and even if the ring is substantially a perfect circle, it is difficult to maintain the shape thereof and concentricity of the fan. Therefore, to prevent striking of the tips 10 of the blades on any part of the ring, the ring is made of larger diameter to provide space 11 at the tips of the blades. This space allows operation of the blades, but it results in loss in efficiency caused by leakage of pressure at the tips of the blades when the fan is in operation.

In accordance with the present invention, I have provided a seal for closing this space which is adapted to be moved into substantial contact with the tips of the blades and adjusted incidental to turning of fan on its rotational axis so that the space is closed circumferentially of the fan regardless of eccentricity or any irregularities in the shape of the ring.

In carrying out the invention, I provide the web 6 of the ring with a sealing member. In the form of the invention illustrated in Fig. 1, the sealing member comprises a circular band 12 formed of a tractable or ductile material having a relatively low elastic limit such as copper, lead and the like to permit ready formation thereof to the path of the fan blade tips. The band 12 is applied to the ring 4 before insertion of a fan 1 and has the side edges 13 and 14 thereof secured adjacent the front and rear sides of the ring to produce an inward bulge 15 as shown in Fig. 1, care being taken that the inner diameter of the bulge is less than the diameter of the fan at the tips of the blades. Therefore, when the fan is inserted, the tips of the blades are contacting the inward bulge of the band and as the fan is rotated slowly by hand, a portion of the bulge will be pushed outwardly by the tips 10 of the blades and give the slight clearance necessary for rotation of the fan blades. By reason of the relatively low elastic limit of the material from which the band is constructed, the band will maintain its imparted shape and when the fan is placed in operation, the tips of the blades will rotate freely within the band with a minimum of clearance therebetween. Consequently, the blades of the fan are effective throughout the entire length thereof and eddy currents are eliminated at the tips of the blades which ordinarily reduce efficiency of a fan. In order to facilitate bulging of the ring into position to be contacted by the tips, the ring 4 may be provided with an

externally threaded tubular fitting 16 to which a supply pipe (not shown) may be connected for introducing a pressure medium into the space 11 so as to move the bulge portion 15 into contact with the tips of the fan blades.

The form of the invention shown in Fig. 1 is satisfactory for the purpose; however, it is possible that during operation or work on the fan, the band may be deformed, in which case it would be difficult to return the band into its original position relative to the fan blades because of inaccessibility to the space 11 without removal of the band. To avoid this difficulty, the sealing band may be attached to a control ring 18 at one edge 19 thereof as shown in Fig. 3. The opposite edge of the sealing band curves inwardly as at 20 and then flares outwardly in a rounding curve as at 21 at the discharge side of the fan. In this case, the fan blades are offset from the supporting ring 18 as shown so that the sealing band forms a part of the control ring. When the fan is to be placed in operation, the sealing band is pressed inwardly so that it is in position to be contacted by the tips of the blades. Then, upon hand turning of the fan, a portion of the ring is pushed outwardly by the blade tips to provide sufficient clearance for rotation of the fan. Should the fan become out of center or the sealing band become distorted for any reason, the sealing band may be returned to contacting relation with the tips of the fan blades by applying pressure on the exterior side of the projecting portion of the band.

In the form of invention shown in Fig. 4, the sealing band 22 is attached along one edge 23 to the control ring 22, while the opposite edge 24 terminates entirely within the limits of the control ring and is left free so that sufficient space 25 is provided between the control ring and band to permit insertion of a tool or other means for pressing the sealing portion 26 of the band into contact with the tips of the blades.

From the foregoing it is obvious that I have provided a seal for fans whereby substantially close tolerance can be established and easily maintained at the tips of the fan blades.

What I claim and desire to secure by Letters Patent is:

1. In combination with a fan having blades rotatable within an annular air control member encircling the fan blades at the tips thereof, space closing means carried by the control member in encircling relation with the fan and in initial contact with the tips of said blades, said space closing means being composed of an easily tractable material for sufficient displacement by the fan blades to permit free rotation of the fan and having low elasticity to maintain said displaced

position for substantially closing the space between the tips of the fan blades and the control member.

2. In combination with a fan having blades 5 rotatable within an annular air control member encircling the fan blades at the tips thereof, an annular band having at least one side edge fixed to the control member and having an inwardly bulging portion initially contacting the tips of 10 the fan blades, said band being composed of an easily tractable sheet material for sufficient outward displacement of said inwardly bulging portion to clear said blades upon rotation of the fan, and said material being of low elasticity to maintain said displaced position during continued operation of the fan.

3. In combination with a fan having fan blades 20 rotatable within an annular air control member encircling the fan blades at the tips thereof, an annular band encircling the fan and having side edges fixed to the control member with the intermediate portion bulged inwardly into initial contact with the tips of the fan blades, said band being composed of an easily tractable material 25 having low elasticity to be displaced by said blades upon initial rotation of said fan and to maintain said displaced position during continued operation of the fan.

4. In combination with a fan having fan blades 30 rotatable within an annular air control member encircling the fan blades at the tips thereof, a band encircling the fan and having side edges fixed to the control member, means for introducing 35 a pressure medium between the attached edges of the band and said control member for bulging the intermediate portion of said band inwardly into contact with the tips of the fan blades, said band being composed of an easily tractable material formable under the pressure medium and having low elasticity to be displaced by said blades upon initial rotation of said fan and to maintain said displacement during continued operation of the fan.
